UNITED STATES PATENT OFFICE.

OLE C. OLSEN, OF MUSKEGON, MICHIGAN.

AIR-SHIP.

No. 895,672.

Specification of Letters Patent.

Patented Aug. 11, 1908.

Application filed December 12, 1907. Serial No. 406,234.

To all whom it may concern:

Be it known that I, OLE C. OLSEN, a citizen of the United States, residing at Muskegon, in the county of Muskegon and State 5 of Michigan, have invented certain new and useful Improvements in Air-Ships, of which the following is a specification.

This invention relates to air ships, and has for its object to provide a ship of this 10 kind embodying certain novel features of construction to be hereinafter described and claimed.

In the accompanying drawings, Figure 1 is an elevation of the invention partly in 15 section. Figs. 2 and 3 are transverse sectional views on the lines 2—2 and 3—3, respectively, of Fig. 1. Fig. 4 is an enlarged sectional detail. Fig. 5 is a plan view showing a modified form of air ship. Fig. 6 is a 20 central transverse sectional view thereof.

The main body of the ship shown in Figs. 1 to 4, is a balloon comprising a cylindrical skeleton frame tapered at its ends and provided with a cover to form the gas retainer. 25 The skeleton frame comprises conical-shaped end-caps 10 connected by longitudinal plates 11. On the outside of these plates are secured stiffening plates 12, which are bent up at the middle to form a strengthening 30 rib 13 running their entire length. The cover is secured between the plates 11 and plates 14 extending parallel thereto, by means of bolts 15 passing through the plates and the fabric of which the cover is made. 35 That portion of the fabric embraced between the plates is doubled as indicated at 16. The plates 14 are also bent outwardly at the middle to form a strengthening rib 17 which also serves as means for attaching one end of 40 the internal brace-wires to be hereinafter described. Near the ends of the balloon are secured external circumferential bands 18.

Adjacent each end of the balloon are compartments 19 and 20 arranged one above 45 the other. The compartments 19 contain the machinery for propelling the balloon, and also the devices for operating the steering gears, to be hereinafter described. The movement of the ship is directed from the 50 compartment 20, a suitable source of communication between said compartment and compartment 19 being provided. To the

outside of the shell 21 which forms the walls of the compartments are secured angle-bars 22, and to the roof 23 of the compartments 55 are secured angle-bars 24 for bracing the same. The compartments are supported by heavy cables or wires 26 connected at one end to the ribs 17 of two of the plates 14 at the top of the balloon, and at the other end 60 to the angle-bars 22 encircling the shell 21.

On the inside of the balloon is mounted a central longitudinal casing which extends throughout the entire length of the balloon and communicates with the compartments 65 19. This casing is in three sections which are in axial alignment. One of these sections, indicated at 27, extends between and is connected at its ends to the roof 23 of each of the compartments at the ends of the 70 balloon. Another section, indicated at 27^a, is secured at one end to one of the casings 10 and at the other end to the roof 23 of the compartments at one end of the balloon, as shown in Fig. 1. The third section 75 27^b is secured in a like manner to the casing 10 and the roof of the compartment at the other end of the balloon.

On the outside of the casing sections is mounted a sleeve 28, which is in four sections, 80 each of which has a radially extending flange 29. These sleeve sections are held in place on the casing by means of a series of rings 30 fitting on the outer ends of the flanges 29. To the flanges 29 are connected one end of 85 internal brace-wires 31, the other end of said wires being connected to the ribs 17. Between the compartments, the balloon is also braced by wires 32 connected at their ends to the ribs 17 of the plates 14 at the 90 top and the bottom of the balloon, respectively.

At each end of the balloon is a driving propeller 33, the shaft 34 of which is mounted in the casing section 27^a. The propellers 95 33 are driven independently by an engine 35 in the respective compartments 19 at the ends of the balloon, the shafts 34 extending into said compartments, and being connected to the engines in any suitable manner. 100

Above the top of the balloon, near each end thereof, are arranged lifting propellers 36 which are also driven by the engines 35. The shafts 37 of these propellers are mounted

in casings 38 extending from the roof of the compartment 19 to the top of the balloon, said casing being secured at one end to the roof, and at the other end to one of the bands 18.

At each end of the balloon, above and below the same, are rudders for steering the balloon sidewise. Each of these rudders comprises a blade 39 presented in a vertical plane and secured to a shaft 40 mounted in a casing 41 extending vertically through the balloon, and secured at its ends to one of the bands 18. On the shaft 40 is a bevel gear 42 which meshes with a similar gear 43 on a shaft 44 mounted in a casing 45, extending from the compartment 19 to the casing 41. Within said compartment the shaft 44 is provided with a hand wheel 46 for turning it, whereby the rudders 39 are operated to steer the balloon sidewise. The casing 41 extends to one side of the casing 27^a in order to clear the same.

At each end of the balloon on both sides thereof, are rudders for guiding the ascent and descent of the balloon. These rudders are blades 47 presented in a horizontal plane and secured to a shaft 48 mounted in a casing 49, extending horizontally through the balloon, and secured at its ends to one of the bands 18. On this shaft is a bevel gear 50, which meshes with a bevel gear 51 on a shaft 52 mounted in a casing 53, connected at its ends to the casing 49, and to the shell 21, respectively. The shaft 52 extends into the compartment 19 and is fitted with a hand wheel 54, whereby the rudders 48 are operated.

The various casings herein described are provided with suitable bearings for the shafts, and means are also provided for supplying a lubricant to the shafts.

The air ship shown in Figs. 5 and 6 comprises a pair of balloons 55 arranged side by side and constructed in substantially the same manner as the balloon hereinbefore described. Between these two balloons is mounted a platform 56 which carries the engines for propelling the ship. The platform is secured to the lower longitudinal plates 13 of the balloon frame. The upper longitudinal plates of the two balloons are connected by arches 57 which carry suspension rods 58 connected to the platform 56. The balloons are also connected near their ends by arches 57^a. Each balloon has a driving propeller 59 at each end, and also lifting propellers 60, and between the balloons at each end are arranged rudders 61 for steering the ship sidewise, and rudders 62 for guiding the ascent and descent of the ship. These rudders are mounted on suitable shafts extending between and secured to the balloon frames, and having operating rods which extend to the platform 56.

The driving propellers of each balloon are mounted on a shaft 63 extending lengthwise through the balloon, and to each of said shafts is geared, as indicated at 64, a transverse shaft 65 having a driving connection with an engine 66 mounted on the platform 56. The lifting propellers are mounted on vertical shafts 67 which are geared to drive-shafts 68 having a driving connection with engines 69 mounted on the platform 56. One engine is provided for driving the lifting propellers at one end of the ship and another engine drives the propellers at the opposite end of the ship, the shafts and gearing connecting these sets of propellers being arranged accordingly. At the middle of the balloons on the inner sides thereof, are casings 70 through which the shafts 65 extend to the main shafts 63.

For the sake of lightness the various shafts may be made hollow, and wherever it is possible aluminum will be employed in the construction of the ship.

I claim:

1. A balloon comprising a cylindrical skeleton-frame tapered at its ends, said frame consisting of end-caps, and parallel plates extending between and connected to said caps; and a cover secured between the plates.

2. A balloon comprising a cylindrical skeleton-frame, said frame consisting of end-caps, parallel plates extending between and connected to said caps, and circumferential bands; and a cover secured between the plates.

3. A balloon comprising a cylindrical skeleton-frame, said frame consisting of end-caps, and parallel plates extending between and connected to said caps; a cover secured between the plates; and a series of braces connected to the plates inside the cover.

4. A balloon comprising a cylindrical skeleton-frame, said frame consisting of end-caps, and parallel plates extending between and connected to said caps; a cover secured between the plates; a tubular member extending lengthwise through the interior of the balloon and connected to the end caps; and a series of braces connected to said member and to the aforesaid plates on the inside of the cover.

5. An air ship comprising a cylindrical skeleton-frame consisting of end-caps and parallel plates extending between and connected to said caps; a gas-bag secured between said plates; a tubular casing extending lengthwise through the interior of the balloon and connected to the end-caps, a shaft mounted in the aforesaid casing; propellers carried by said shaft; and means for driving the propeller shaft.

6. An air ship comprising a pair of balloons arranged side by side, a platform

there between, driving-propellers at the ends of the balloons, lifting propellers above the balloons, and a pair of rudders mounted between the balloons at each end thereof, one member of each pair of rudders being presented in a vertical plane, and the other member being presented in a horizontal plane.

In testimony whereof I affix my signature, in presence of two witnesses.

OLE C. OLSEN.
